UNITED STATES PATENT OFFICE

111,884

DESIGN FOR A VEHICLE LICENSE PLATE

Josh F. Williams, Lexington, Miss., assignor of one-third to W. R. Ellis and J. W. Latham, Lexington, Miss.

Application August 15, 1938, Serial No. 79,358

Term of patent 3½ years

To all whom it may concern:

Be it known that I, Josh F. Williams, a citizen of the United States, residing at Lexington, in the county of Holmes and State of Mississippi, have invented a new, original, and ornamental Design for a Vehicle License Plate, of which the following is a specification, reference being had to the accompanying drawing, forming part thereof.

hicle license plate, showing my new design.

Figure 2 is a top plan view thereof.

I claim:—

The ornamental design for a vehicle license plate, as shown.

JOSH F. WILLIAMS.
